*Primary Examiner—Ian Simmons
Attorney, Agent, or Firm—Bernhard Kreten***[57] CLAIM**

The ornamental design for a no reflux syringe, as shown and described.

DESCRIPTION

FIG. 1 is a perspective view of a no reflux syringe showing my new design.

FIG. 2 is a top view thereof, the bottom being a mirror image thereof.

FIG. 3 is a side view thereof, the opposite side being a mirror image thereof.

FIG. 4 is a rear view thereof.

FIG. 5 is a front view thereof.

FIG. 6 is a side partially evacuated view thereof; and, FIG. 7 is a side fully evacuated view thereof.
